UNITED STATES PATENT OFFICE.

JOHN G. BRENNER, OF TOLEDO, OHIO.

SWING.

SPECIFICATION forming part of Letters Patent No. 642,673, dated February 6, 1900.

Application filed August 17, 1899. Serial No. 727,551. (No model.)

To all whom it may concern:

Be it known that I, JOHN G. BRENNER, of Toledo, county of Lucas, and State of Ohio, have invented certain new and useful Improvements in Swings; and I do hereby declare that the following is a full, clear, and exact description of the invention, which will enable others skilled in the art to which it appertains to make and use the same, reference being had to the accompanying drawings, and to the characters of reference marked thereon, which form part of this specification.

My invention has reference to a swing, and is adapted to be used in public parks, public playgrounds, &c.

My invention is not designed for use alone by children, but is especially adapted for elderly people; and with this object in view it is constructed to combine the factors of comfort and safety.

In carrying out my invention I provide a chair suspended from a suitable trestle and having a tilting seat and back and a foot-board which serves as an anchor for the swing when the person about to enter the chair steps thereon and which raises automatically when the person is seated.

My invention further embodies certain novel features of construction and the parts and combination of parts hereinafter shown, described, and claimed.

In the drawings, Figure 1 is an elevation of my invention, showing the chair suspended from the trestle, also showing the foot-board in a lowered position in contact with the ground to anchor the chair. In this view the legs of the trestle and the straps by which the chair is suspended are shown cut away because of limited space upon the sheet. Fig. 2 is an isometric view showing the means of attachment of the straps which support the chair.

The trestle upon which the swing is hung is formed of two inverted-V-shaped supports, composed of pieces 1 and 2, arranged a short distance apart to permit the chair 3 to swing between them. Pieces 1 and 2 are bolted together at their upper ends at 4 and are spread apart at their lower ends to give stability to the trestle. Near the upper ends of pieces 1 and 2 are secured pieces 5, which support a cross-piece 6, through which pass bolts 7, hav-

ing bifurcated heads 8, adapted to receive the ends of straps 9. After the straps 9 have been inserted into the bifurcated heads 8 they are 55 securely fastened by passing rivets 10 therethrough. Straps 9 may be made of wood; but I prefer to construct the same of metal and preferably of steel. The lower ends of straps 9 are secured to bolts 11, similar in all respects to bolts 7. The frame of the chair is composed of two similar segmental circular side sections 12, to which bolts 11 are secured, the brackets 13, the arm-pieces 14, joined to the standards 16, and the seat-frame 15, extending between the standards 16 and the side sections 12. The ends of sections 12 are secured together by rod 17, having interposed intermediate of its length an ordinary turn-buckle 18, by which means the circularity of sections 12 is maintained. 19 is the chair-back, pivotally connected to parts 13 at 14' and having a coiled spring 20 attached to the upper end thereof, which is also attached to section 12 at 20'. The seat of the chair 21 is 65 pivotally connected to seat-frame 15 at 22 and is connected by a link 23 to a piece 24, pivoted at 25 and having on the end thereof the footboard 26.

I wish it to be understood that in this description where reference is made to the parts on one side of the chair the other side is also referred to, as both sides of the chair are identical in construction.

When a person is about to enter the chair, 85 he steps upon the footboard 26, causing it to take its normal position in contact with the ground, as shown in full lines, Fig. 1. The footboard while in this position will securely anchor the chair against movement and overcome the usual danger of the moving parts of the swing striking the shins of the person. After the person has seated himself the seat of the chair will take the position a, (shown in dotted lines, Fig. 1,) which will cause the 95 footboard, through the medium of the connecting-link 23, to rise from the ground and permit the free movement of the swing. This movement may be imparted to the swing by a person standing behind the same, or a rope 100 (which I have not deemed necessary to be shown in the drawings) may be attached to the legs 1 and 2, respectively, of the trestle in convenient reach of the person seated in

the chair. By means of the construction which I have described the back of the chair will assume a variable position *b*, (shown in dotted lines, Fig. 1,) which, together with the 5 variable seat of the chair, will conform to any angular position which the body of the person seated in the chair may assume.

I wish to lay particular stress upon the practical method which I employ to suspend 10 the chair from the trestle. By employing metal straps, which by their resiliency permit the chair to swing, and the bifurcated bolts 7 there is no wear whatever at the point of attachment. I wish also to mention the 15 practical construction of my chair. By forming the frame of two segmental circular sections and having all other parts of the chair depend therefrom I furnish an extremely- rigid construction and practically insure the 20 chair from coming apart through exposure to weather.

Having described my invention, what I claim, and desire to secure by Letters Patent, is—

25 1. In a swing, the trestle, the chair suspended therefrom, having the segmental cir-

cular side sections, the seat-frame supported thereby, the tilting seat movably secured in the seat-frame, the movable footboard pivotally attached to the side sections, and a link 30 connection between the footboard and the seat, substantially as and for the purpose set forth.

2. In a swing, the trestle, having the cross-piece 6; the chair having segmental circular 35 side sections 12, the adjustable back 19, the tilting seat 21, the movable footboard pivotally attached to the side sections, and a link connection between the footboard and the seat; bolts having bifurcated heads passing 40 through the cross-piece 6, and the side sections 12, and straps for suspending the chair from the trestle, adapted to be secured in said bifurcations, substantially as described.

In testimony that I claim the foregoing as 45 my own I affix my signature in presence of two witnesses.

JOHN G. BRENNER.
